UNITED STATES PATENT OFFICE.

DANIEL J. SALTSMAN, OF MEMPHIS, TENNESSEE.

END-GATE FOR PRESS-BOXES.

SPECIFICATION forming part of Letters Patent No. 642,724, dated February 6, 1900.

Application filed July 11, 1899. Serial No. 723,444. (No model.)

To all whom it may concern:

Be it known that I, DANIEL J. SALTSMAN, a citizen of the United States, residing at Memphis, in the county of Shelby and State of Tennessee, have invented a new and useful End-Gate for Press-Boxes; and I do hereby declare the following to be a full, clear, and exact description of the invention, such as will enable others skilled in the art to which it applies to make and use the same.

My invention relates to improvements in apparatus employed for expressing oil from seeds, such as cotton-seed, and from nuts, beans, peas, cereals, meat, and other oil-bearing substances; and my invention consists in the novel compressible gates employed for closing the press-boxes and in the novel means employed for supporting such gates.

In the extraction of oil from substances such as those above mentioned by pressure a series of press boxes or plates mounted one upon another within a suitable hydraulic or other press and arranged to telescope one within another when pressure is applied are employed. The meal, seeds, or pulp from which the oil is to be extracted is placed within these boxes before they are so pressed together, and in order that the oil-bearing substance may be prevented from escaping from the boxes

through the openings therein through which the charge is introduced it is customary to wrap the charge for each box in cloths. The wrapping of the charges in this manner and the stripping of the cloths from the cake remaining after the oil has been pressed out require considerable time and labor, and therefore involve considerable expense. The cost of the press-cloths is also a considerable item, since they are subjected to considerable strain and last but a short time. When press-cloths are used, the ends of the cakes taper at the openings in the press-boxes and so do not receive the same amount of pressure as the other parts of the cakes, and hence retain more oil than those portions of the cakes which are exposed to the full pressure.

By the use of the end-gate for press-boxes herein illustrated and described the use of press-cloths is avoided, with a consequent reduction in expense and greater convenience of operation, a brighter and softer cake is

made, and the yield of oil is greater, because all portions of the cake are subjected to equal pressure.

The object of my invention is to avoid the expense, inconvenience, and loss due to the employment of press-cloths and to make the device employed for retaining the oil-bearing substance in the press-boxes as simple, inexpensive, and effective as possible. This object is attained in the invention herein described and illustrated in the drawings which accompany and form a part of this specification, in which the same reference-numerals indicate the same or corresponding parts, and in which—

Figure 1 is a front elevation of an oil-press the press-boxes of which are provided with my end-gates. Fig. 2 is a vertical section of a series of press-boxes from front to rear, showing the end-gates in place within the press-boxes; and Fig. 3 is a view similar to Fig. 1, showing another method of supporting the end-gates.

In the drawings, 1 is the press, and 2 2 the press-boxes, of ordinary construction, arranged to telescope one within the other in the ordinary manner and provided with mats 3 for supporting the cakes and with drainage-channels 4.

5 and 5' are the end-gates above mentioned. These gates are blocks of rubber or other readily-compressible and elastic material of such size that they fit into the openings at the front and rear of the press-boxes. They are preferably from one-half to three-quarters of an inch shorter than the openings in the press-boxes, so that opportunity for the expansion of the gates longitudinally under pressure is afforded. The rear gates 5' may be held in place by cleats or lugs 6, secured to the press-boxes, as shown in Fig. 2, or formed integrally with the boxes. The front gates are preferably hinged to the press-boxes, as shown in Fig. 1, each gate being secured to a hinge-leaf 7, hinged to the box above; but as an alternative to this construction arms 8, to which the front gates 5 are secured, as shown in Fig. 3, may be mounted upon a vertical shaft 9 and held apart by springs 10, which permit the gates to ascend with the press-boxes when pressure is applied,

but which support the gates about opposite their respective openings when pressure is removed and the gates are swung outward.

Instead of being hinged to the press-boxes 5 or to a rod or shaft 9 the front end-gates may be entirely separate from the apparatus, being removed and inserted as desired.

The manner of operating the apparatus is as follows: The boxes being relieved of pressure 10 and open to the full extent, the front end-gates 5 are opened either by swinging them to one side, if they be supported as shown in Figs. 1 and 3, or by removing them altogether and a charge of oil-bearing material 15 placed in each press-box. This may be done conveniently by employing a suitable shovel, upon which the charge for each box may be placed. The shovel having been inserted in the press-box, the corresponding end-gate 20 may be closed over the shovel, which is then removed, leaving the charge within the box, the end-gates preventing the escape of any portion of it. The boxes having been filled in this manner, pressure is applied in the customary manner and the oil pressed out. The 25 end-gates compress as the press-boxes telescope into each other, and thus do not interfere with the application of pressure to the oil-bearing material in the boxes. The pressure upon the end-gates holds them in place. The oil having been pressed out, the pressure 30 on the boxes is removed, the front end-gates opened, and the cakes remaining in the boxes are removed in any suitable manner, as by 35 the use of a shovel.

If desired, the boxes may be so constructed as to require no rear end-gates, being provided with end partitions, similar to the side pieces of the boxes, which fit into each other 40 in such manner as to prevent the escape of the material within the boxes.

Having thus completely described my invention, what I claim, and desire to secure by Letters Patent, is—

45 1. The combination, with press-boxes arranged to fit one within the other, and each open at one end for the reception of a charge of material to be pressed, of end-gates of elastic and compressible material adapted to fit

into and close the said ends of the boxes, and 50 to compress as said boxes are pressed together.

2. The combination, with press-boxes arranged to fit one within the other, and each open at one end for the reception of a charge of material to be pressed, of rubber end-gates 55 adapted to fit into and close the said ends of the boxes and to compress as the boxes are pressed together.

3. The combination, with press-boxes arranged to fit one within the other, and each 60 open at one end for the reception of a charge of material to be pressed, of end-gates of elastic and compressible material, adapted to fit into and close the said ends of the boxes, and to compress as said boxes are pressed together, 65 and swinging supports for said end-gates.

4. The combination, with press-boxes arranged to fit one within the other, and each open at one end for the reception of a charge of material to be pressed, of end-gates of elastic 70 and compressible material, adapted to fit into and close the said ends of the boxes, and to compress as said boxes are pressed together, and hinged supports for said end-gates, secured to the boxes.

5. The combination, with press-boxes arranged to fit one within the other, and open at the ends for the reception of a charge of material to be pressed, of end-gates of elastic and compressible material adapted to fit into 80 and close both front and rear openings in the boxes, and to compress as said boxes are pressed together.

6. An end-gate for closing openings in telescoping press-boxes, consisting of a block of 85 rubber or other elastic and compressible material, adapted to fit into and close an opening in a press-box, and to compress as said boxes are pressed together, thereby permitting the application of pressure to the contents of the boxes.

In testimony whereof I have hereunto affixed my signature in the presence of two witnesses.

DANIEL J. SALTSMAN.
